UNITED STATES PATENT OFFICE.

WILLIAM E. JOHNSON, OF ST. JOSEPH, MISSOURI.

VULCANIZER.

1,392,645.

Specification of Letters Patent.

Patented Oct. 4, 1921.

Application filed December 18, 1920. Serial No. 430,304.

To all whom it may concern:

Be it known that I, WILLIAM E. JOHNSON, residing at St. Joseph, in the county of Buchanan and State of Missouri, have invented new and useful Improvements in Vulcanizers, of which the following is a specification.

This invention relates to portable vulcanizers, and comprehends a construction by means of which the shoe of a pneumatic tire can be quickly and easily repaired without removing the tire from the wheel.

The chief characteristics of the present invention resides in the provision of a device of the body designed to provide a combustion chamber in which is arranged a plurality of wings or partitions, the latter being so disposed to afford the vulcanizer maximum combustion space as well as a large amount of heating surface, the wings or partitions radiating heat to the vulcanizing face of the device which is brought into direct contact with the shoe or case.

The nature and advantages of the invention will be better understood when the following detail description is read in connection with the accompanying drawings, the invention residing in the combination, construction and arrangement of parts as claimed.

In the drawings forming part of this application, like numerals of reference indicate the similar parts in the several views and wherein:

Figure 1 is a side elevation of a tire showing the manner of using the invention.

Fig. 2 is a sectional view taken on line 2-2 of Fig. 1.

Fig. 3 is a perspective view of the vulcanizer.

Fig. 4 is a detail view of the hood removed.

Fig. 5 is a section on Fig. 4.

The device forming the subject matter of my invention comprises a casing or the like 10 which is substantially of rectangular configuration, and divided by a vertically disposed partition 11 into what I term a combustion chamber 12 and a cool air chamber 13. The casing is open at its top, while the front wall of the casing is provided with a plurality of draft openings 14 arranged with relation to the bottom of the casing to define the fuel capacity of the casing, and in this manner only the proper amount of fuel 55 can be arranged within the container to efficiently vulcanize the shoe 15 to which the de-

vice is applied. The rear wall of the case 16 constitutes the vulcanizing face which is brought into contact with the shoe or case, and is slightly curved to conform to the 60 shape of the shoe as illustrated. Arranged within the combustion chamber 12 is a pair of diametrically arranged wings or partitions 17 which intersect at a point adjacent the partition 11, while forming an integral part 65 of these wings or partitions is a partition 18 arranged centrally of the casing 10 and also intersecting the partitions 17 at their point of intersection. The partition 18 is substantially T-shaped the head of which is indicated at 19. These partitions provide for a maximum heating surface and radiate heat from the combustion chamber 12 to the cool air chamber 13. The construction as well as the relative arrangement of the various wings or partitions is not only efficient for this purpose, but also affords the container a large combustion space. The partitions contact the partition 11 which forms one wall of the cool air chamber, while the 70 partitions terminate in spaced relation to the bottom of the container to provide a fuel chamber the fuel being indicated at 20. The cool air chamber is also divided by partitions 21 which serve to radiate the heat from 75 the partition 11 to the vulcanizing face 16 of the container. A hood of the configuration illustrated in Fig. 4 is adapted to be arranged upon the vulcanizer to prevent the heat from coming in contact with the adjacent parts of the tire being repaired or other parts of the vehicle which would be detrimental to such parts. This hood includes 80 opposed side walls 22 which are connected by a top wall having an upwardly inclined 85 portion 23 which is arranged above the combustion chamber 12, and a horizontally disposed portion 24 which covers the cool air chamber 13. Projecting inwardly from the end walls 22 are pins or the like 25 which 90 repose upon the upper edge of the casing 10 to support the hood in proper position thereon. In addition to protecting the parts of the vehicle from the detrimental effect of the heat, it is quite obvious that the hood 23 95 prevents the escape of heat from the device, thereby rendering the vulcanizer highly efficient for the purpose intended. Projecting from the opposed sides of the container 10 are slotted lugs 26 through which are 100 adapted to be passed threaded bolts 27 and having associated therewith thumb nuts 28.

The bolts are carried by the terminals of a chain or the like 29 which is adapted to be passed under the felly or rim of the wheel as shown in Fig. 2, and when the bolts are 5 associated with the lugs 26 the vulcanizer is immovably and properly supported upon the shoe or casing 15. The device is very simple in construction and efficient in operation, and can be manufactured and sold at a 10 very nominal cost.

While it is believed that from the foregoing description the nature and advantages of the invention will be readily apparent, I desire to have it understood that I do not limit 15 myself to what is herein shown and described, and that such changes may be resorted to when desired as fall within the scope of what is claimed.

What I claim is:—

20 1. A vulcanizer of the character described comprising a container divided into combustion chamber and a cool air chamber, partitions arranged within the combustion chamber and disposed to radiate heat to said 25 cool air chamber, said partitions terminating short of the bottom of the container to form a fuel chamber, one wall of the container having draft openings, and means for securing the vulcanizer to the wheel of the vehicle.

2. A vulcanizer comprising a container open at its top and divided into a combustion chamber and a cool air chamber, partitions arranged within the combustion chamber for radiating heat to said cool air chamber, said partitions terminating short of the 35

container, and forming a fuel chamber, one wall of said container having draft openings arranged a predetermined distance above the bottom to determine the capacity of the 40 sides of the container whereby the device is secured to the wheel of a vehicle.

3. A vulcanizer of the character described comprising a container open at its top and divided into a combustion chamber and a 45 cool air chamber, a plurality of partitions arranged within the combustion chamber for radiating heat to said cool air chamber, all of said partitions intersecting at a common point, said partition terminating short of the bottom of the container to define a fuel chamber, one wall of said container having a plurality of draft openings, and means for securing the vulcanizer to a 50 wheel of a vehicle.

55 4. A vulcanizer of the character described comprising a container open at its top and divided into a combustion chamber and a cool air chamber, a plurality of partitions arranged within the combustion chamber for 60 radiating heat to the cool air chamber, said partitions intersecting each other at a common point and terminating short of the bottom of the container to define a fuel chamber, one wall of said container having a plurality of draft openings, a hood removably mounted upon the open end of the container, and means for securing the vulcanizer to a 65 wheel of a vehicle.

In testimony whereof I affix my signature. 70

WILLIAM E. JOHNSON.
